(57) **CLAIM**

The ornamental design for a portable lamp, as shown.

DESCRIPTION

FIG. 1 is a top side view of a portable lamp

FIG. 2 is a top view of the portable lamp

FIG. 3 is a front view of the portable lamp

FIG. 4 is a left side view of the portable lamp

FIG. 5 is a back side view of the portable lamp

FIG. 6 is a right side view of the portable lamp; and,

FIG. 7 is a bottom side view of the portable lamp.

This is an application for a new, original and ornamental design for a portable lamp having a stretched rectangular base area with rounded off corners and containing three LEDs.
